UNITED STATES PATENT OFFICE.

EDWARD H. FOOTE, OF SOMERVILLE, MASSACHUSETTS.

DESIGN FOR A MILK-BOTTLE-CAP REMOVER.

59,645.

Specification for Design.

Patented Nov. 15, 1921.

Application filed April 15, 1919. Serial No. 290,347. Term of patent 7 years.

To all whom it may concern:

Be it known that I, EDWARD H. FOOTE, a citizen of the United States, residing at Somerville, county of Middlesex, State of Massachusetts, have invented a new, original, and ornamental Design for a Milk-Bottle-Cap Remover, of which the following is a specification, reference being had to the accompanying drawing, forming part thereof.

In the drawings, Figure 1 is a perspective view of a milk bottle cap remover embodying my new design; Fig. 2 is a side view thereof.

I claim:

The ornamental design for a milk bottle cap remover, as shown.

EDWARD H. FOOTE.
